DUAL PURPOSE GAFF AND FISHHOOK DISLODGER

Franklin D. J. Bordenave, 7725 Devine Ave.,
New Orleans, La. 70127

Filed Aug. 30, 1972, Ser. No. 284,973

Term of patent 14 years

Int. Cl. D22—05

U.S. Cl. D22—22

Fig. 1

Fig. 2

Fig. 4

Fig. 5

Fig. 3

Fig. 6

FIG. 1 is a view in perspective of a dual purpose gaff and fishhook dislodger showing my new design.

FIG. 2 is an edge elevational view thereof.

FIG. 3 is a bottom view.

FIG. 4 is a view in perspective of a modified form of the design shown in FIG. 1.

FIG. 5 is an edge elevational view of FIG. 4 observing the same in a direction from right to left.

FIG. 6 is a bottom view of the same.

I claim:

The ornamental design for a dual purpose gaff and fishhook dislodger, as shown and described.
